ATTORNEY

UNITED STATES PATENT OFFICE.

HENRY C. FOLGER, OF WAVERLY, MASSACHUSETTS, ASSIGNOR TO HOUSING COMPANY, OF BOSTON, MASSACHUSETTS, A CORPORATION OF MASSACHUSETTS.

REFRIGERATING APPARATUS.

Application filed November 3, 1922. Serial No. 599,630.

To all whom it may concern:

Be it known that I, HENRY C. FOLGER, a citizen of the United States, residing at Waverly, in the county of Middlesex and State of Massachusetts, have invented certain new and useful Improvements in Refrigerating Apparatus, of which the following is a specification.

The invention to be hereinafter described relates to refrigeration apparatus.

This apparatus comprises a closed container or containers holding a frozen liquid which may be transferred from a chamber in which the liquid is frozen to a cooling chamber for refrigerating purposes. The liquid in these containers will remain at low temperatures for substantial periods, but eventually when the containers have lost their desired cooling effect, they are removed from the cooling chamber, and other such containers are substituted therefor so as to continue or renew the refrigerating effect.

One of the purposes of the present invention is to provide simple and efficient means for supporting the containers in the cooling chamber. The construction is such that the containers may be quickly and easily mounted on their supports in the cooling chamber and removed therefrom, and the character of the supporting means is such that substantially the entire surfaces of the containers will be exposed to the air efficiently to cool the same.

Another purpose of the invention is to provide means for automatically producing air currents in the cooling chamber which will promote the refrigeration thereof by the frozen liquid holding containers.

The apparatus may be employed for a variety of uses, but for purposes of illustration, in the present instance, it is described more particularly with respect to a refrigerating body mounted on a motor truck which may be used for conveying ice cream or other materials requiring refrigeration.

The character of the invention may be best understood by reference to the following description of one good form thereof shown in the accompanying drawings, wherein:

Fig. 1 is a perspective view of a motor truck having a body equipped with refrigerating apparatus embodying the invention, a portion of one of the walls of the truck

body being broken away to disclose parts contained therein;

Fig. 2 on an enlarged scale is a partial section through the cooling chamber of the truck, showing containers mounted therein, and portions of cans for ice cream beneath the containers;

Fig. 3 is a vertical section taken on line 3-3 of Fig. 2; and

Fig. 4 is a perspective view of features to be described.

Referring to the drawings, a suitable motor truck may be provided having a body 1 constructed to provide a cooling chamber 3 having front, rear and side walls, each comprising an outer finishing layer 5 of suitable wood, a layer 7 of balsa wood, a layer 9 of blotting paper, and a layer 11 of cork. The top of the chamber may comprise a thick layer 13 of balsa wood, and an outer finishing layer 15 of suitable wood. The ends of the balsa wood layers meeting at the corners of the chamber may have mitre joints connected by dove-tail key strips 17 inserted longitudinally into dove-tail grooves of the joints. The chamber constructed as described may be substantially air-tight, and has desirable insulating effect in resisting entrance of warm outer air through the walls into the cooling chamber.

At one side of the cooling chamber is a hinged door 19, which may be formed of balsa wood and an outer finishing layer of wood. The door may be secured in closed position by a latch 21.

Having described the cooling chamber, next will be described the means for effecting the cooling thereof. This means, in the present instance of the invention, comprises a container or containers which may be variously formed to serve the purposes. Each container may be in the form of an elongated casing 23 having a thickness relatively thin as compared to its width. At the opposite ends of the casing are heads 25 and 27, the latter being provided with an opening normally closed by a plug 29 threaded therein. Projecting from one edge of the casing are a pair of hooks 31 formed of ribbon material.

These containers may be nearly filled with a suitable liquid to be frozen, such, for example, as a solution which may be salt and

water, or alcohol and water, or calcium chloride and water, or any other appropriate solution. It is desirable to employ solutions such as mentioned, since each has a low freezing point.

The liquid or solution may be introduced into the container on removal of the plug 29 therefrom. To introduce the liquid or a solution into the containers, they may 10 be supported in an upright position, preferably with the plug opening uppermost, and then a hose may be connected to the upper end of each container, and the upper end of the hose may lead from a tank 16 containing the liquid or solution, and located above the level of the containers. The liquid may gravitate downward from the tank through the hose, and rise upward in the containers until it reaches a level spaced 20 somewhat from the upper heads thereof.

After the containers have been supplied with the liquid, the plugs are returned to the openings in the containers, and the latter are in readiness for the freezing operation.

The temperature of the liquid in the containers may be lowered to the freezing point or below said point if desired. Under certain conditions it may be preferable to 30 carry the temperature down to 32° F., and under other conditions it may be preferable to carry the temperature down to 10° F., and sometimes as low as 15 or 20° below zero. The freezing of the liquid in the 35 containers may be accomplished in the same room or chamber in which the ice cream is frozen or hardened, but preferably the freezing of the liquid in the containers is done in a separate chamber.

40 It is customary to employ the ammonia system in the room for freezing or hardening ice cream, and the piping in this room may be extended into an adjacent and separate room adapted to receive the containers containing the liquid to be frozen. Thus, the liquid in the containers may be frozen in a special room without devoting any of the space therein to ice cream hardening, and the containers may be inserted 45 into the special room therefor and removed therefrom without the necessity of opening the door for the ice cream hardening room, and hence raising of the temperature in the latter room such as would necessarily occur 50 on introduction of the containers into and removal from the room is avoided.

55 After the liquid in the containers has been frozen, the containers are transferred from the freezing room therefor to the truck body, and may be introduced into the cooling chamber therein on opening of the door 59.

Suitable means may be provided to support the containers in the cooling chamber.

65 To accomplish this, in the present instance

of the invention, a series of hangers 33 may be provided, each in the form of a rod bent to present end feet 35 and an intermediate foot 37 secured to the top of the cooling chamber, and preferably these rods extend 70 transversely to the length of the truck body.

The construction is such that on insertion of the containers into the body, they may be lifted to present their hooks 31 to the hangers 33 for support thereby. The length 75 of the containers may vary, but in the present instance, the length is such that the containers may be mounted in pairs on the hangers, with the containers of each pair in end-to-end relation.

80 Since the containers are supported by the hooks on the hangers, and the containers are in spaced relation, substantially the entire surfaces thereof are exposed to the air in the chamber and are available for efficient 85 cooling effect.

86 It is desirable to prevent the containers or most of them from swinging on their hangers against one another. To accomplish this, in the present instance, a holding strip 39 may be provided having holes at intervals receiving pins 41 which may be dropped into holes in ears 43 projecting from the adjacent ends of each pair of containers, the construction being such that the containers to which the holding bar is connected, will be prevented from swinging.

As stated, one of the purposes of the invention, is to provide means for producing 100 air currents in the cooling chamber to promote the efficient cooling effect accomplished by the containers holding the frozen liquid.

This means, in the present instance of the invention, comprises a pair of bellows 45 at opposite ends of the chamber. The 105 bellows have movable backs 47 provided with fingers 49 projecting into ears 51 at ends of the containers adjacent to the bellows. The lower ends 53 of the bellows are open to direct air currents downward in 110 the direction of the arrows (Fig. 3) when the bellows are collapsed.

The motions which the truck body is subjected to during travel of the motor truck, will cause the end containers to swing on 115 their hangers, and this motion will be transmitted through the fingers 49 to the backs of the bellows, and thereby produce the downwardly directed air currents which will result in a circulation of the air in 120 the cooling chamber which will cause the air cooled by the containers holding the frozen liquid to pass downward and efficiently cool or refrigerate the cans of ice cream, or other materials introduced into 125 the chamber 57 beneath the containers.

130 The containers will serve to lower the temperature of the cooling chamber and maintain their cooling effect for substantial periods of time. When the containers have

lost their substantial cooling effect, they may be removed from the cooling chamber and be returned to the freezing room for the purpose of again freezing the liquid therein.

5. Preferably, two sets of containers are provided for each truck, one set to be in the freezing chamber in readiness to be substituted for the set in the truck body when required. Thus, the refrigeration or cooling 10 effect in the truck body may be continued indefinitely or renewed from time to time as required.

The number of containers employed may vary according to the size of the cooling 15 chamber and the degree of refrigeration desired.

The truck body may also be constructed to provide a chamber 55 adapted to receive broken ice and a chamber 57 adapted to 20 receive salt. The ice chamber may have doors 59 and 61 at the tops thereof through which the ice and salt may be introduced into the chambers. At one side of the body is a discharge door 63 mounted in guides 65, 25 said door being provided with a handle 67 and a latch 69. This door may be opened to enable broken ice and salt to be taken from the chambers 55 and 57 for the purpose of packing the ice cream cans in tubs 30 to keep the cans cold.

It will be understood that the invention is not limited to the specific embodiment shown, and that various deviations may be made therefrom without departing from the 35 spirit and scope of the appended claims.

What is claimed is:—

1. Refrigeration apparatus comprising, in combination, a cooling chamber, a container movably mounted therein and adapted to 40 hold a frozen liquid, and a bellows operated by movements of said container for producing air currents in said chamber for promoting the cooling effect of said container.

2. Refrigeration apparatus comprising, in combination, a cooling chamber, containers movably mounted therein and adapted to hold a frozen liquid, and bellows operated by movements of said containers for producing air currents in said chamber for promoting the cooling effect of said containers. 45

3. The combination of a vehicle having a body provided with a cooling chamber, a bellows mounted in said chamber, a container in said chamber adapted to hold a frozen 55 liquid and susceptible of swinging movements occasioned by motion of the body when travelling, and means to connect the container with the bellows for operating the latter from the former.

60 4. The combination of a vehicle having a body provided with a cooling chamber, a plurality of containers therein, at least one of said containers being susceptible of move-

ments during travel of the vehicle, and a bellows operated by said movements for 65 producing air currents in the cooling chamber.

5. The combination of a vehicle having a body provided with a cooling chamber, supports at the top of the chamber, a plurality 70 of containers detachably connected to said supports and each adapted to hold a frozen liquid, bellows at opposite ends of the chamber connected to the containers adjacent thereto in order that swinging movements of 75 said containers occasioned during travel of the vehicle may operate the bellows to produce air currents in the chamber, and means connecting the containers intermediate the bellows operating containers to prevent 80 them from swinging.

6. The combination of a vehicle having a body provided with a cooling chamber, a plurality of containers mounted therein, each adapted to hold a frozen liquid, and 85 means detachably to connect the containers with one another permitting their individual introduction into the chamber and removal therefrom.

7. The combination of a vehicle having a body provided with a cooling chamber, a series of supports extending transversely of the body at the top of the chamber and distributed at intervals throughout the length of the chamber, and containers having 95 hooks adapted to be removably connected to said supports, each of said containers being adapted to hold a frozen liquid, said body being provided with a door through which the containers may be introduced into said chamber and removed 100 therefrom.

8. The combination of a vehicle body provided with a cooling chamber, supports secured to the top of the chamber and distributed at short intervals throughout the length of the top, and a plurality of frozen liquid holding containers having hooks at the upper ends thereof connected to said supports, a pair of the containers being supported on each support, and means connecting the containers to prevent them from 105 swinging against each other.

9. The combination of a vehicle body provided with a cooling chamber, a series of supports secured to the top of the chamber and distributed at short intervals along the length thereof, pairs of frozen liquid holding containers connected to said supports in tandem relation, ears projecting from adjacent ends of each pair of the containers, and a holding strip detachably secured to said ears for preventing the containers from 115 swinging against each other. 120

HENRY C. FOLGER.
